SPEED INDICATING PLATE FOR LATHE HEADSTOCK

Harold J. Siekmann, George J. Kasselmann, and William Okvit, Cincinnati, Ohio, assignors to The R. K. Le Blond Machine Tool Co., Cincinnati, Ohio, a corporation of Delaware

Application September 30, 1955, Serial No. 38,190

Term of patent 14 years

(Cl. D54—6)

Fig. 1

Fig. 2

Fig. 3

Fig. 1 is a front perspective view of the speed indicating plate for lathe headstock incorporating our new design.

Fig. 2 is a front elevation of the speed indicating plate in Fig. 1.

Fig. 3 is an end elevation of the speed indicating plate shown in Fig. 2.

The broken line portions in Fig. 1 are for the purpose of illustration.

We claim:

The ornamental design for a speed indicating plate for lathe headstock, as shown and described.

No references cited.
